CLAIM

The ornamental design for a bottle, as shown and described.

DESCRIPTION

FIG. 1 is a right side elevational view of a bottle showing my new design; the side opposite being a mirror image of the side shown;

FIG. 2 is a top plan view thereof;

FIG. 3 is a rear elevational view thereof;

FIG. 4 is a front elevational view thereof;

FIG. 5 is a bottom plan view thereof; and
FIG. 6 is a fragmentary cross sectional view taken of the line 6—6 of FIG. 2.

FIG. 6

FIG. 1

FIG. 3

FIG. 2

FIG. 4

FIG. 5
